DESIGN FOR A DISPLAY SIGN

George L. Lee, Maplewood, N. J.

Application February 25, 1939, Serial No. 83,206

Term of patent 14 years

To all whom it may concern:

Be it known that I, George L. Lee, a citizen of the United States, residing at Maplewood, in the county of Essex and State of New Jersey, have invented a new, original, and ornamental Design for a Display Sign, of which the following is a specification, reference being had to the accompanying drawing, forming part thereof.

The figure is a front perspective view of the sign showing my new design.

The rear and opposite ends of the sign are substantially the same in appearance as the front and the end shown, respectively.

I claim:

The ornamental design for a display sign, as shown and described.

GEORGE L. LEE.
